MESNE ASSIGNMENTS, TO DELCO-REMY CORPORATION, OF DAYTON, OHIO, A COR-
PORATION OF DELAWARE.

IGNITION SYSTEM.

Application filed June 24, 1926. Serial No. 118,301.

This invention relates to ignition apparatus for multicylinder engines, and includes among its objects the providing of ignition apparatus which will furnish ignition sparks in relatively rapid succession.

Further objects and advantages of the present invention will be apparent from the following description, reference being had to the accompanying drawings, wherein a preferred form of the present invention is clearly shown.

In the drawings:

Fig. 1 is a wiring diagram illustrating a form of the present invention;
15 Fig. 2 is a diagram illustrating the sequence of operation of the different circuit breakers of an ignition system adapted for an eight-cylinder engine; and

Fig. 3 is a diagram similar to Fig. 2, illustrating the adaptation of the invention to a 20 twelve-cylinder engine.

Referring to the drawings, 20 designates an internal-combustion engine having a plurality of cylinders, for example, eight cylinders, each provided with a spark plug. In Fig. 1 the various spark plugs are numbered from 1 to 8, inclusive, respectively. For example, the small circle referred to by numeral 1 in Fig. 1 designates the spark plug 25 for cylinder #1. The engine 20 drives at cycle speed a shaft 21 which drives an ignition timer shaft 22 at one-half cycle speed through the gear train 24, 26, and which drives an ignition timer shaft 23 at one-half 30 cycle speed through the gear train 25, 27. Cycle speed refers to the time required for the engine to complete one cycle of operation. If, for example, the engine has eight cylinders, cycle speed refers to the time required for exploding all of the cylinders. If the engine is a four-stroke-cycle engine, the shaft 21 would be operated at one-half engine crankshaft speed. If the engine is a two-stroke-cycle engine, the shaft 21 would 35 be operated at engine speed. As the present invention is applicable to two-cycle and four-cycle internal combustion engines, an engine driven shaft operated at cycle speed is taken as a basis for defining the speed of the 40 timer shafts 22 and 23 relative to the speed of the engine. The shaft 22 rotates in the

direction of the arrow 22^a, and drives an ignition timer cam 32 having $\frac{N}{C}$ equally-spaced cam lobes 34, N being the number of engine cylinders, and C the number of ignition coils used. An 8-cylinder engine having its ignition provided by two coils will require a timer cam 32 having four lobes 34. The lobes 34 cooperate with rubbing blocks 36 and 38 of a pair of circuit breaker levers 40 and 42, respectively, which are pivoted at 44 and 46, respectively, upon a breaker plate represented by the circle 48. The circuit breaker 40 carries a contact 50 cooperating with a stationary contact 52 which is grounded upon the breaker plate 48. A leaf spring 54 carries current from a terminal 56 to the breaker lever 40 and contact 50, and yieldingly urges the movable contact 50 into engagement with the stationary contact 52 or the rubbing block 36 into engagement with the cam 32. The circuit breaker 42 carries a contact 60 adapted to cooperate with a stationary contact 62 grounded upon the breaker plate 48, and a leaf spring 64 conducts current from a terminal 66 to the lever 42 and contact 60 and yieldingly urges the contact 60 toward the contact 62, and the rubbing block 38 toward the cam 32. The terminals 56 and 66 are connected with the primary winding 72 of an ignition coil 70. The primary winding 72 is connected by wire 74 and a switch 76 with a battery 77 which is grounded at 78. The secondary winding 80 of the ignition coil 70 is grounded through the battery 77 and is connected with a double-ended rotor 82, each end of which extends the same distance from the center of rotation and serves as a member 85 for distributing sparking impulses to any one of the four distributor terminals 84 which are carried by a distributor head 86. These distributor terminals have an angular spacing of $\frac{180}{N}$ degrees, for example, 45° 90 in ignition apparatus for an 8-cylinder engine and using two coils. As the distributor 95 86 serves only one-half the total number of engine spark plugs, for example, spark plugs 2, 4, 6, and 8, the distributor head 86 may carry only four terminals 84. For conven- 100

ience, these terminals 84 have been marked #2, #4, #6, and #8 to designate that they are to be connected by wires, as shown, with the spark plugs 2, 4, 6 and 8, respectively.

5 The breaker levers 40 and 42 are located relative to the cam 32 so that the levers will be moved to open and closed positions alternately in regular sequence. The cam 32 rotates in a clockwise direction, as indicated by 10 the arrow 22^a, and will cause the breaker 40 to close and open while the breaker 42 remains open, and likewise, will cause the breaker 42 to close and open while the breaker 40 remains open. In Fig. 2, the 15 horizontal lines 40 represent diagrammatically the periods during which the breaker lever 40 is in closed position, and the horizontal space between adjacent ends of these lines 40 represents the period during which 20 the breaker lever 40 is in open position. Similarly, the horizontal lines 42 in Fig. 2 represent the periods during which the breaker lever 42 is in closed position and the space between adjacent ends of the lines 42 25 represent the periods during which the breaker lever 42 is in open position. The dot designated #2 at the end of one of the lines 40 represents the instant of the generation of a sparking impulse in the ignition 30 coil 70. This particular dot is referred to by #2 since it represents the sparking impulse for cylinder #2. At the instant the lever 40 opens to separate contacts 50 and 52, one of the ends of the double-end rotor 35 82 will be opposite the distributor terminal #2, so that the sparking impulses generated will be distributed to the spark plug #2. As represented in Fig. 2, the breaker lever 42 will close and open to produce the generation 40 of a sparking impulse in coil 70 at the instant represented by the dot #4 which represents the instant of generation of a sparking impulse for spark plug #4. Similarly, the breaker lever 40 will close and 45 open to cause the ignition coil to generate a sparking impulse for cylinder #6 represented by dot #6 in Fig. 2, and then breaker 42 will close and open to cause the coil 70 to generate a sparking impulse for cylinder 50 #8 represented by dot #8 in Fig. 2. At the instant the sparking impulse for plug #6 is generated, the rotor 82 will be opposite the distributor terminal #6, and then opposite terminal #8 when the sparking 55 impulse for plug #8 is generated. If the arm 82^a of the rotor 82 has been distributing during one cycle of operation of the engine, as represented by the horizontal distance between the arrow heads *a* and *b* in Fig. 2, 60 during the next succeeding cycle distribution will be effected by the diametrically opposite arm 82^b of the rotor 82.

Having described in detail how ignition is provided for spark plugs 2, 4, 6, and 8, it 65 will be readily apparent from the drawing

how ignition is provided for spark plugs 1, 3, 5 and 7. The parts which are associated with the timer shaft 23 and which correspond in function to parts associated with the shaft 22 have been designated by odd 70 numbers exceeding by one unit the reference numbers applied to corresponding parts associated with the timer shaft 22. For example, the timer cam is referred to by numeral 33 and rotates in a counterclockwise 75 direction, as indicated by numeral 33^a. The breaker lever 41 is controlled by the cam 33 in order to cause an ignition coil 71 to generate sparking impulses for spark plugs numbers 1 and 5 which are connected, as 80 shown, with certain of the distributor terminals 85 of a distributor head 87, namely, the terminals marked #1 and #5. Similarly, the breaker lever 43 is operated by the cam 33 in order to cooperate with the ignition 85 coil 71 to effect the generation of the sparking impulses for spark plugs #3 and #7, which are connected, as shown, with those distributor terminals 85 which have been marked #3 and #7, respectively. The 90 breaker lever 41 effects the closing and separation of its contacts, while the contacts controlled by lever 43 are opened, and the lever 43 effects the closing and opening of its contacts, while the contacts affected by lever 41 are open. The levers 41 and 43 are arranged to be closed and opened alternately by the cam 33 in order that a succession of sparks will be generated by the coil 71 for the plugs 1, 3, 5 and 7. 100

In Fig. 2 the horizontal lines 41 designate the closed periods of the breaker lever 41, and the dots #1 and #5 represent successive instants of opening of the lever 41 in order to effect the generation of sparking impulses for spark plugs #1 and #5, alternately. In Fig. 2 the horizontal lines 43 designate the closed periods of the breaker lever 43 and the dots numbered 3 and 7 designate, respectively, the instants of the generation of 105 sparking impulses for the spark plugs 3 and 7. The rotor 83 operated by the shaft 23 is likewise double-ended, that is, provided with oppositely-extending ends 83^a and 83^b, which are equidistant from the axis of rotation of the rotor. At the instant represented by the dot #1 in Fig. 2, one of the rotor ends 83^a, for example, will be adjacent the distributor terminal #1. Similarly, at the instant of the generation of sparks represented 110 by the dots #3, #5 and #7, the distributor end 83^a will be opposite the distributor terminals #3, #5 and #7, respectively. Since the rotor 83 operates at one-half cycle speed, the rotor ends 83^a and 83^b will operate alternately in distributing a succession of sparking impulses to the distributor terminals 1, 3, 5 and 7. 115

Referring to Fig. 2 again, it will be noted that the timing and distributing mechanisms 120

associated with the shafts 22 and 23 function alternately. Considering one cycle of the engine as being the period between successive explosions of cylinder #1 it will be noted that breaker 41 first opens to effect the generation of sparking impulse for plug #1, breaker 40 then opens to effect the generation of a sparking impulse for plug #2. These operations are then followed by the opening of breaker 43 for plug #3; opening of breaker 42 for plug #4; opening of breaker 41 for plug #5; opening of breaker 40 for plug #6; opening of breaker 43 for plug #7; and opening of breaker 42 for plug #8. The zig-zag dot-and-dash line is applied only to direct the attention more clearly to the order of the opening of the breaker levers. The closing periods of the successively-operating breakers overlap, for example, the closing periods of levers 41 and 40; 40 and 43; 43 and 42; and 42 and 41. The present arrangement of circuit breakers and cams causes the energizing of one of the ignition coils to begin while the other ignition coil is building up and then discharging. In this manner, the time for energizing the coils may be increased beyond that which would be possible if but a single coil were used to provide ignition impulses for all of the engine cylinders.

It will be understood that the engine may have any desired explosion or firing order, for example, the order 1, 2, 3, 4, 5, 6, 7 and 8. If the firing intervals are equal, an explosion will be required every one-eighth of the total engine cycle period. If, for example, ignition is required for an 8-cylinder, two-cycle internal-combustion engine capable of operating at 6000 R. P. M., the interval between successive sparks would be 1/800 of a second. By using two coils which are discharged alternately each coil is caused to generate sparks every 1/400 of a second, which is a rate within the possibilities of an ignition coil. As the timing mechanism must be operated at a relatively high rate in order to meet these ignition requirements it is desirable to use breakers in parallel and operate them alternately. The wear on the rubbing blocks and contact points is thus distributed and the life of the timing mechanism is substantially doubled. The use of breaker levers in parallel also permits the use of a relatively small cam since the number of lobes is only one-half the number required if a single breaker lever were used. The shape of the cam lobes can be made such as to produce the minimum of wear upon the rubbing blocks.

The present invention is adapted for engines having asymmetric firing intervals as well as engine having equal firing intervals. By "asymmetric" is meant, firing intervals which are alternately equal instead of successively equal. If the firing intervals are

all equal, then the timing and distributing mechanism associated with the shafts 22 and 23 are operated alternately at equal successive intervals, for example, for a two-cycle cylinder engine the intervals between the successive sparks are $\frac{1}{8}$ of a revolution of a shaft, such as 21, rotating at cycle speed, or every 45° of rotation of shaft 21. Since shafts 22 and 23 operate at one-half cycle speed, the operations produced by shaft 22 are $22\frac{1}{2}^\circ$ out of phase with the corresponding operations produced by shaft 23. If, for example, the engine is a 60° , V-type, 8-cylinder engine requiring firing intervals of 60° and 30° alternately, the operations produced by shaft 22 are 15° out of phase with the corresponding operations produced by shaft 23. The interval between sparks 1, 3, 5 and 7; and 2, 4, 6 and 8 is 90° of rotation of shaft 21 or cycle operation, but the interval between sparks 1 and 2 may be 30° , for example, between #2 and #3, 60° ; #3 and #4, 30° , etc., referring to rotation of shaft 31.

It is also apparent that the present invention is not limited to providing ignition for an 8-cylinder engine, but is applicable to engines having any number of cylinders such as 6, 12, 16 and 18 cylinders, and the like.

The following table shows various examples of the applications of the present invention to multicylinder engines having regular firing intervals.

Number of cylinders=N	Number of coils, cams, distributors=C	Number of cam lobes N/C	Distributor terminal spacing 180 C/N	Relativity of timer shafts 180/N	100
6	2	3	60	30	100
8	2	4	45	22 $\frac{1}{2}$	105
12	2	6	30	15	110
12	3	4	45	15	115
16	4	4	45	11 $\frac{1}{4}$	120
18	3	6	30	10	125

Fig. 3 shows the sequence of operation of three pairs of breaker levers operated by three cams, respectively, and controlling three coils respectively, each providing ignition impulses for one-third of the engine cylinders. The dots designated #1 to #12 represent the instants of the sparking impulses for cylinders #1 to #12 respectively. The sparking impulses for cylinder #1, #4, #7 and #10 are generated by one coil which is controlled by a pair of breaker levers the closing periods of which are represented by the horizontal lines preceding these dots. Similarly, the sparking impulses for cylinders #2, #5, #8 and #11 are generated by a second coil which is controlled by a second pair of circuit breakers, and the sparking impulses for cylinders #3, #6, #9 and #12 are provided by a third coil which is controlled by a third pair of circuit breakers. The pairs of circuit breakers are out of phase

4
by 30° of engine cycle rotation or 15° of timer shaft rotation.

While the form of embodiment of the present invention as herein disclosed, constitutes a preferred form, it is to be understood that other forms might be adopted, all coming within the scope of the claims which follow.

What is claimed is as follows:

- 10 1. Ignition apparatus for a multicylinder internal combustion engine having N cylinders, comprising in combination, a current source, C ignition coils each for providing
15 the sparking impulses for $\frac{N}{C}$ cylinders, C timer cams each having $\frac{N}{C}$ lobes and operated
20 at one-half cycle speed, and a pair of circuit make-and-break devices operated alternately by each cam, each pair of make-and-break devices controlling the energizing and discharging of one ignition coil, means driven by the engine for causing the cams to operate alternately to effect the discharging of
25 the coils in recurrent sequence, and means for distributing the sparking impulses produced to the engine spark plugs in recurrent sequence.

2. Ignition apparatus according to claim

1, in which the distributing means comprises C distributor heads each having distributing terminals for connection with the spark plugs of $\frac{N}{C}$ cylinders and spaced $\frac{180^\circ \times C}{N}$

35 and cooperating, respectively, with distributing rotors each connected with an ignition coil and operated at one-half cycle speed, the rotors distributing alternately in recurrent sequence to their respective distributor terminals.

40 3. Ignition apparatus according to claim 1, in which the distributing means comprises two distributor heads each having $\frac{N}{C}$ distributing terminals for connection with the spark plugs of $\frac{N}{C}$ cylinders and spaced $\frac{180^\circ \times C}{N}$
45 degrees and cooperating, respectively, with double-end distributing rotors each connected with an ignition coil and operated at one-half cycle speed, the rotors distributing alternately in recurrent sequence to their respective terminals.

50 In testimony whereof we hereto affix our signatures.

HERBERT C. WALTERS.
JOHN T. FITZSIMMONS.
